DUPLICATING MACHINE

Frank Ronald Ford, Sparkbrook, Birmingham,
England

Application June 15, 1944, Serial No. 540,483
In Great Britain March 17, 1943

1 Claim. (Cl. 101—132.5)

1

This invention relates to duplicating machines, and refers more particularly to machines of the kind having a cylinder to which is clamped a master sheet bearing in reverse script the matter to be reproduced, a pressure roller parallel to the cylinder, and a moistening device by which the copy sheets can be moistened before reaching the nip between the cylinder and the pressure roller where they are pressed into contact with the master sheet as they pass through the machine.

In such machines, the moistening device usually comprises a moistening pad or the like and a supporting surface or damping bar, the copy sheets being passed between these two members in pressure contact with the pad and one of such members being moved away from the other once in each revolution of the cylinder to allow a fresh copy of sheet to reach the nip between the pressure roller and the cylinder. Usually the moment at which the moistening members separate is indicated by the operation of a check device which resists rotation of the cylinder. When the latter reaches a predetermined angular position.

The check device is conveniently set to operate when the leading edge of the master sheet on the cylinder is approaching, and near to, the nip between the cylinder and the pressure roller.

The object of the present invention is to provide an improved or simplified construction of machine.

According to the present invention, the check device and the moving member of the moistening device are mechanically connected, so as to be operable simultaneously by a single actuating member, the moving member aforesaid being separated from the stationary moistening member to allow insertion of a copy sheet at the moment when the rotation of the cylinder is checked, and the return movement of the moistening member taking place automatically when the rotation of the cylinder is resumed or continued.

The check device may be of known form incorporating a disc concentric with the cylinder and arranged at one end thereof, a spring-pressure roller engaging the circular periphery of this disc and at each revolution entering a notch in such periphery so as to check the rotation of the cylinder without forming a positive stop, the angular position of this notch in relation to the cylinder being such that the checking action occurs when the leading edge of the master sheet is approaching, and is near to, the line of contact between the cylinder and the pressure roller.

In applying the present invention to such an arrangement, the roller co-operating with the disc is mounted for rotation in a bracket on an oscillating lever which is pivoted to the frame

of the machine, a link connection being provided between this oscillating lever and the moving member of the moistening device.

This link connection may be such that relative movement is possible between the link and the lever, such movement being under the control of a light spring. The link may, for instance, pass through a clearance hole in the lever, and at one side of the lever may be provided with an adjustable abutment, while at the opposite side of the lever a light spring acts between the latter and a second adjustable abutment on the link. The end of the link remote from the spring may be connected to an oscillating damping bar adapted to press the copy sheets against the moistening pad.

In order that my invention may be clearly understood and more readily carried into practice, I have appended hereto drawings illustrating the same, wherein

Figure 1 is a part sectional side elevation of a duplicating machine embodying the invention.

Figure 2 is a fragmentary plan view of the machine.

Figure 3 is a side view, to an enlarged scale, showing the arrangement of the moistening device and its operating means in relation to the cylinder and pressure roller of the machine, and

Figure 4 is a perspective view showing one side of the moistening device.

In the drawings the invention is shown applied to a duplicating machine of the kind in which the pressure roller 5 is disposed below the cylinder 6, the latter being provided with a clip 7 whereby the leading edge of a master sheet may be secured thereto and both the pressure roller and the cylinder being mounted for rotation between spaced side frames 8 which are connected by tie-bars 9.

In front of the nip 10 between the pressure roller 5 and cylinder 6 is mounted a moistening device comprising a liquid reservoir 11, and a moistening pad 12 to which liquid is conveyed by wicks (not shown) or other means, this pad 12 being disposed within a suitable holder 13 arranged transversely of the machine.

Copy sheets, such as 14, fed in from a feed table 15, pass beneath the pad holder 13 and are pressed against the exposed underside of the pad 12 by means of a damping bar 16, so that the copy sheets 14 are moistened on their upper sides.

Formed on or provided at one end of the cylinder 6 is a concentric disc 17 having a substantially semi-circular notch 18 in its periphery.

The check device associated with the machine comprises a roller 19 mounted in a bracket 20 of U section which is secured to the underside of a swinging lever 21, one end of the latter being pivoted at 22 to the adjacent side frame 60 8 of the machine.

The roller 19 is pressed against the periphery of the disc 17 by means of a spring plunger acting on the lever 21, and this plunger may consist of a pin 23 sliding in a clearance hole provided in one of the tie-bars 9 or in a small bracket attached to one of the side frames 8. A spring 24 on this pin 23 is compressed between the underside of the tie-bar 9 or bracket and a nut 25 engaging a screw-thread 26 on the pin 22, so that the pressure exerted on the lever 21 is adjustable.

The angular position of the notch 18 aforesaid in relation to the cylinder 6 is such that the roller 19 enters the notch and checks the cylinder when the clip 7 is approaching and close to the nip 10 between the cylinder 6 and pressure roller 5.

At its free end the swinging lever 21 is provided with a clearance hole 28 through which can slide a link 27, this latter conveniently being of circular section for the greater part of its length and having its lower end pivotally connected to the damping bar 16.

Preferably the damping bar 16 takes the form of a metal strip, which is arranged for pivotal movement about an axis parallel to, and adjacent, one of its longitudinal edges; for example, the bar 16 may be provided at each end with a peg 29 which enters a hole 30 or recess in a bracket 31 secured to the underside of the pad holder 13.

The free edge of the damping bar 16 may be bevelled, as at 32, for engagement with the undersides of the copy sheets 14, and the link 27 may be connected to one end of the bar 16 adjacent its free edge.

In the convenient arrangement shown, the lower end of the link 27 is flattened and of hook-like form as at 33, so that when necessary, it can readily be disengaged from a pivot pin or screw 34 projecting from the end of the damping bar.

The hooked end 33 of the link 27 may be formed by shaping the metal so that the hook opening has an entrance portion 35 extending parallel with the axis of the link at one side thereof and an inner portion 36 which extends at right angles towards the centre line of the link, this inner portion of the opening being adapted normally to receive the pivot pin or screw 34 on the damping bar 16.

The end of the link 27 which passes through the clearance hole 28 in the lever 21 is threaded, as at 38, and is provided with an adjustable abutment adapted to engage the underside of the lever 21, which abutment may take the form of a pair of nuts 29.

Loosely mounted on the link 27 is a washer 40 engaging the upper side of the lever 21, and a light spring 41 embracing the link 27 is compressed between this washer 40 and a pair of lock nuts 42 at the upper end of the link, these lock nuts forming a second adjustable abutment.

It will be understood that, while the roller 19 on the lever 21 is engaging the circular periphery of the disc 17 (that is to say; throughout the greater part of the revolution of the cylinder 6,) the spring-loaded link 27 connecting the lever 21 to the damping bar 16 keeps the bevelled edge 32 of the latter raised, so that the copy sheet 14 under treatment is maintained in light pressure contact with the moistening pad 12 as it passes to the nip 10.

As the clip 7 securing the leading edge of the master sheet to the cylinder 6 approaches closely to the nip 10, the appropriate moment for intro-

duction of a fresh copy sheet is indicated by the operation of the check device.

The entry of the roller 19 into the notch 18 in the disc 17 allows the lever 21 to move downwardly under the pressure of the spring-loaded pin 23, whereupon the link 27, acted upon by the free end of the lever 21 through the medium of the nuts 39; positively separates the damping bar 16 from the moistening pad 12 so as to permit passage of a fresh copy sheet between these members.

Obviously, if desired, there may be a check device at each end of the cylinder 6, and the two swinging levers 21 associated with such device may be connected as above described to opposite ends of the damping bar 16.

What I claim then is:

A duplicating machine comprising a rigid frame, an impression cylinder rotatably mounted in said frame, means for securing one edge of a master sheet to said cylinder, a pressure roller adapted to bring copy sheets into contact with the master sheet on said cylinder, a stationary moistening pad, means for supplying liquid to said pad, a damping bar between which and said pad said copy sheets pass before reaching the nip between said cylinder and said pressure roller, said damping bar being movable into and out of a position in which it presses said copy sheets against said pad, a disc arranged to rotate with said cylinder and disposed at one end thereof, a lever pivoted to said frame, a spring pressing said lever towards the periphery of said disc, a roller carried by said lever, said roller contacting the periphery of said disc and adapted at each revolution of the latter to enter a notch therein so as to check the rotation of said cylinder without forming a positive stop, said lever being oscillated by movement of said roller into and out of said notch, a lateral projection on said damping bar, a link having a hooked end thereof engaged with said projection and the other end passed through a hole in said lever, the opening in said hooked end being L-shaped to permit application of both a push and a pull to said damping bar, spaced adjustable abutments on said link at opposite sides of said lever, said lever acting on one of said abutments so as to positively separate said damping bar from said pad when said roller enters said notch to permit a fresh copy sheet to be fed into the machine and a light spring interposed between said lever and the other of said abutments, said lever after resuming its normal position on further rotation of said cylinder producing adjustable resilient pressure contact between said damping bar and said pad through the medium of said light spring.
